UNITED STATES PATENT OFFICE.

MYRTLE I. MAYER, OF LONG BEACH, CALIFORNIA.

GARMENT HANGER.

Application filed September 29, 1923. Serial No. 665,668.

To all whom it may concern:

Be it known that I, MYRTLE I. MAYER, a citizen of the United States, residing at Long Beach, in the county of Los Angeles and State of California, have invented certain new and useful Improvements in Garment Hangers, of which the following is a specification.

This invention relates to supports or hangers for garments of the kind in which a horizontally disposed cross piece is equipped between its opposite ends with a hook adapted to engage a support and in which the arms of the cross piece are adapted to engage the neck or shoulder portion of the garment which it holds. Garment hangers of this kind are commonly used for supporting coats and vests and are especially adapted to support ladies' clothing, such as dresses, skirts, shirt waists, and other such garments.

The principal object of my invention is to provide a garment hanger of such construction and so equipped that it may conveniently support ladies' skirts, dresses, etc., of different sizes and kinds, and my invention consists in equipping the arms of the cross piece with clamps which are adapted to engage the garment and yieldingly hold it in place and which are adjustable to different positions on the cross piece and properly hold garments of various kinds in such manner as to retain them in proper shape.

In the accompanying drawings:—

Figure 1 is a perspective view of a garment supporter equipped with clamps made in accordance with my invention.

Figure 2 is a similar view of a garment hanger of slightly different shape.

Figure 3 is a front elevation of my improved garment hanger showing how it may be applied to a lady's garment.

Figure 4 is a detail view of a device employed for adjustably holding the clamp on the hanger.

Figure 5 is another view of the same device and shows on an enlarged scale the shape of the clamp preferably employed.

The cross pieces A shown in Figure 1 and 2 are of the usual kind, that shown in Figure 1 being square in cross section, while that shown in Figure 2 is of circular cross section. The cross piece A is provided with a hook B as usual. Each arm of the cross piece is provided with a clamp

C which is pivotally connected with the cross piece by a coiled spring D which has its ends connected at d in order to provide a spring ring which surrounds the cross piece. By these devices the clamps may be moved to any desired position on the hanger to accommodate garments of different kinds and as the spring rings D closely fit the arm of the cross piece, the clamps may be held securely in position until designedly moved by the user. Each clamp C is preferably of the kind shown. The spring ring D passes through its middle portion; its outer end is formed with a tooth or hook e adapted to engage the edge of an opening in the garment, such as the neck portion as indicated in Figure 3, while its inner end is beveled or inclined at e to permit the catch to rock or turn on its axis while being applied to a garment.

It will be observed that the clamp has a straight flat portion b which rests on the top of the cross piece. This construction prevents the clamp from wabbling or getting out of proper working position, but the springs yield sufficiently to permit the clamp to slide back and forth on the cross piece and also to rock thereon when being applied to a garment or being withdrawn therefrom.

A hanger provided with clamps of the kind shown can be made at small expense. The clamps may be sold separately and applied to hangers of usual construction and will serve to hold garments of various kinds and sizes in such manner as to prevent them from slipping out of place. I prefer to provide an adjustable clamp on each arm of the hanger, but one clamp often serves to prevent the garment from slipping from its support.

Garment hangers of the kind shown are largely used for domestic purposes and also are used to a large extent in stores of various kinds and in pressing and cleaning establishments.

I claim as my invention:

1. A garment hanger comprising a cross piece, clamps slidably endwise thereon and having a pivotal movement to and from clamping position and springs which yieldingly support the clamps on the cross piece and permit said movement.

2. A garment hanger comprising a cross piece, clamps slidably mounted on the cross piece and springs which serve the double

purpose of yieldingly and pivotally connecting the clamps to the cross piece.

3. A garment hanger comprising a cross piece, garment-engaging clamps and spring rings slidably mounted on the cross piece; said clamps pivotally connected therewith by said rings.

4. A garment hanger comprising a cross piece, a clamp having a tooth or hook at one end and which is beveled at its opposite end, and a coiled spring surrounding an arm of the cross piece, extending through the clamp, and serving to yieldingly and

pivotally connect the clamp with the cross piece.

5. A garment hanger comprising a cross piece, a clamp having a hook or tooth at one end and which is beveled at the opposite end and which has a plain flat surface engaging the cross piece, and a coiled spring ring pivotally connecting the clamp with the cross piece and which is slidably mounted on an arm of the cross piece.

In testimony whereof, I have hereunto subscribed my name.

MYRTLE I. MAYER.
